UNITED STATES PATENT OFFICE.

SIDNEY GEORGE BROWN, OF WILLESDEN LANE, NORTH ACTON, ENGLAND.

ELECTRIC AURAL APPARATUS MORE ESPECIALLY FOR USE BY DEAF PERSONS.

Application filed October 24, 1921. Serial No. 510,031.

To all whom it may concern:

Be it known that I, SIDNEY GEORGE BROWN, a subject of the King of Great Britain, residing at Victoria Road, Willesden Lane, North Acton, in the county of Middlesex, England, have invented certain new and useful Improvements in or Relating to Electric Aural Apparatus More Especially for Use by Deaf Persons; of which the following is a specification.

This invention relates to aural apparatus more especially for use by deaf persons, and has for its chief object to provide an improved construction whereby the sound is transmitted in a highly efficient manner through to the skull or teeth by a vibrating member.

In order that the said invention may be clearly understood and readily carried into effect, the same will now be described more fully with reference to the accompanying drawings, in which:—

Figure 1 is a longitudinal section and Figure 2 is a plan, with cover removed, of a sound transmitting device embodying this invention.

A is the casing with removable cover *a*. B is a horse-shoe permanent magnet having poles in the form of a single pole-piece *b* which extends across the ends of the magnet, the pole-piece being preferably made from a single plate formed with a hole or gap *b'* leaving narrow connecting bars at each side. C is a stiff reed made of considerable rigidity and mounted at its inner end upon the base D fitted within the casing A, the reed being secured upon the projection or column *d* of the base by the screws *c*. E is a sound transmitting contact stud, which is shown fixed upon the outer end of the reed outside the casing. F, F are a pair of small electro-magnets on the pole-piece *b*, the coils of which magnets are connected to the sockets *a'* in the insulating block *a²* on the bottom of the casing A, the wires *f* passing through a hole *d'* in the base D.

The reed C possesses considerable rigidity so that its oscillations are of small amplitude and of relatively large power, the reed when secured in place lying immediately above but not quite in contact with the pole-piece *b* above the gap *b'*. The permanent

magnet is preferably made strong so as to exercise substantial attraction upon the reed but the screws *c* secure the reed so that it does not come into actual contact with the pole-piece. The electro-magnets F are connected up through the sockets *a'* to the telephone transmitter of any suitable character, so that the speech currents cause variations in the magnetic field through the soft iron or steel pole-piece *b*, giving rise to corresponding vibrations of the stiff reed C, the natural period of which may be considerably above the periods of ordinary speech currents.

The outer end of the reed C projects through a gap *a³* in the casing A and the stud E, which may be of vulcanite, is secured upon the end of the reed so as to project clear of the casing. The position of the stud on the reed may be varied and may be placed between the electro-magnets and the mounting of the reed, in which case the stud might project through the top of the casing. However mounted, the stud must be in a convenient position for application to the teeth or to the skull of the person using the apparatus, so that the small amplitude but relatively powerful vibrations of the reed are transmitted directly to the bones of the head and consequently to the inner ear independently of the ear drum. As the conduction of sound is not through the air but is through solid bodies a small amplitude of vibration is sufficient to produce the loud sounds required and the rigidity or stiffness of the reed C is therefore an essential feature, a weak reed having vibrations of large amplitude but relatively small power which would be ineffective as applied to the teeth or skull of the deaf person for whom the device is especially intended.

What I claim and desire to secure by Letters Patent of the United States is:—

1. In an electrical aural device, the combination comprising a magnet, a pole piece joining the two ends of said magnet, energizing coils therefor, a stiff vibrating member rigidly fixed at one end and in operative juxtaposition to said pole piece and a sound-conducting member mounted upon the free end of said vibrating member for conveying sound vibrations to deaf persons.

- otherwise than by the ear drum, as set forth.
2. In an electrical aural device, the combination comprising a horse-shoe magnet, a pole piece joining the two ends of said magnet and having a hole therein, energizing coils therefor, a stiff reed rigidly secured at one end and situated over the hole in said pole piece and a sound conducting member mounted upon the free end of said reed for conveying sound vibrations to deaf persons otherwise than by the ear drum, as set forth. 10

SIDNEY GEORGE BROWN.
